(57) **CLAIM**

The ornamental design for an insole with three cushions as shown and described.

DESCRIPTION

FIG. 1 is a top, rear, right side perspective view of an insole with three cushions showing my new design;

FIG. 2 is a bottom, rear, right side perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof;

FIG. 9 is a top, rear, right side perspective view of another embodiment of an insole with three cushions showing my new design;

FIG. 10 is a bottom, rear, right side perspective view thereof;

FIG. 11 is a top view thereof;

FIG. 12 is a bottom view thereof;

FIG. 13 is a left side view thereof;

FIG. 14 is a right side view thereof;

FIG. 15 is a front view thereof;

FIG. 16 is a rear view thereof;

FIG. 17 is a top, rear, right side perspective view of another embodiment of an insole with three cushions showing my new design;

FIG. 18 is a bottom, rear, right side perspective view thereof;

FIG. 19 is a top view thereof;

FIG. 20 is a bottom view thereof;

FIG. 21 is a left side view thereof;

FIG. 22 is a right side view thereof;

FIG. 23 is a front view thereof; and,

FIG. 24 is a rear view thereof.

In the drawings, the broken lines depict portions of the insole with three cushions that form no part of the claimed design.

1 Claim, 15 Drawing Sheets
